UNITED STATES PATENT OFFICE.

WILLIAM M. GAMBILL, OF MERKEL, TEXAS.

DENTAL ARTICULATOR.

Application filed October 19, 1925. Serial No. 63,509.

This invention relates to a dental articulator, and has for its object to provide, in a manner as hereinafter set forth, an articulator of the class referred to, which when operated will efficiently grind in the teeth to obtain thoroughly satisfactory occlusion for producing and perfecting the three point contact, the rotation point, the inward slant, the downward slant, and the incisal slant on the occlusal surface of the teeth.

A further object of the invention is to provide, in a manner as hereinafter set forth, an articulator having means to provide, a combined oscillatory and vertical movement during the grinding action and further with means for positioning a re-truded and a protruded bite therein.

Further objects of the invention are to provide, in a manner as hereinafter set forth, a dental articulator, which is simple in its construction and arrangement, strong, durable, adjustable, thoroughly efficient and convenient in its use, readily coupled with a driving means therefor, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a top plan view of a dental articulator in accordance with this invention.

Figure 2 is a side elevation thereof.

Figure 3 is a section on line 3—3, Figure 1.

Figure 4 is a section on line 4—4, Figure 1.

Figure 5 is a section on line 5—5, Figure 3.

Figure 6 is a top plan view of the upper articulator member with the driving means therefor not shown.

Figures 7, 8 and 9 are end views of different form of controlling means for the upper articulator member to provide for

the grinding of the different slants on the cusps of the teeth.

Referring to the drawings in detail, 1 denotes a stationary triangular base member provided with a series of depending supports 2 of substantial height and further provided with a series of openings 3. The base 1 is adapted to have secured thereto the set of teeth, not shown, intended for the lower jaw. The inner enlarged end of the base member 1 is provided centrally with an opening 4 having a threaded wall, and the narrow or outer end of the base member 1 is reduced, as at 5, to provide a ledge 6 and a shoulder 7. The reduced portion 5 has an opening 8 formed with a threaded wall.

Arranged in superposed relation with respect to the base member 1 is the upper articulator member referred to generally by the reference character 9 and which comprises a substantially rectangular body portion 10 having a rounded outer end 11. The inner end 12 of the body portion 10 is formed with a rectangular cutout portion 13 and is furthermore provided with a pair of oppositely extending right angularly disposed connector arms 14, 15, adapted to be coupled to a face bow when desired. The body portion 10, intermediate its ends, is formed with an enlarged rectangular opening 16 for connection therewith, in any suitable manner, of the set of teeth, not shown, for the upper jaw. Formed in the body portion 10, at the longitudinal center thereof, and opening into the cutout portion 13 is a socket 17 having a threaded wall, and extending transversely of the body portion 10 from the inner side thereof and communicating with the socket 17 is a channel 18 having a threaded wall. Formed in the upper face of the body portion 10, near the outer end thereof, is a circular cavity 19 formed with a rectangular extension 20

positioned in proximity to the outer side edge of said body portion 10, and the latter in proximity to said outer side edge is provided with a longitudinally extending bore 21 intersected by the extension 20. The bore 21 extends from the rear end edge of the body portion 10 and terminates in proximity to the rounded outer end 11 of said body portion.

Formed integral with the lower face of the body portion 10, forwardly with respect to the opening 16 and disposed con-

centrically with respect to the cavity 19, is a depending sleeve 22 registering with an opening 23 which communicates with and is disposed centrally with respect to the cavity 19. The sleeve 22 forms a bearing member. The body portion 10 is formed with openings 24, in close proximity to the cavity 19.

Positioned within the bore 21 is an operating shaft 25 provided with a worm 26 mounted in the extension 20 of the cavity 19. The shaft 25 extends from the rear end of the body portion 10 and has connected therewith a flexible shafting 27 for revolving it. The wall of the bore 21 provides a bearing for the shaft 25, and the latter extends to the forward end of the bore 21 and beyond the extension 20 of the cavity 19. The worm 26 is positioned on the shaft 25 inwardly with respect to the forward end of the latter.

Extending through the forward end of the body portion 10 and sleeve 22, as well as projecting above said body portion 10 and depending below said sleeve is a vertically disposed shaft 28, operated from the shaft 25 and which is provided with any suitable means coacting with a controlling element for imparting an oscillatory and a vertical movement to the upper articulator member 9. As illustrated by way of example, the means carried by the shaft 28 is a cam 29 positioned in close proximity to the pointed lower end 30 of the shaft 28. The controlling element which coacts with the cam 29 is referred to generally at 31 in Figures 2, 3, 4 and 5, and said controlling element 31 will be hereinafter more specifically referred to. The lower portion of the shaft 28 extends into the controlling element 31 and the pointed end 30 of the shaft 28 as well as the cam 29 coacts with the inner face of the controlling element 31 to provide for the movement imparted to the upper articulator member. The shaft 28 has its upper portion peripherally threaded, as at 32, for engagement with interior threads formed on the inner face of a gear wheel 33 having a hub extending from each side of the wheel 33 and with the upper portion 34 of said hub of greater length than the lower portion 35 thereof. The hub is referred to generally by the reference character 36. The lower portion 35 of the hub 36 seats on bottom of the cavity 19 and spaces the worm wheel 33 therefrom. The upper portion 34 of the hub 36 extends above the top of the body portion 10 and through a closure plate 37 for the top of the cavity 19, and said plate 37 is secured to the body portion 10 by hold-fast devices 38 which engage with the walls of the openings 24. The shaft 28 extends above the portion 34 of the hub and carries a wing nut 39 for locking the worn gear 33 in position. The worm gear

33 and nut 39 bodily revolve with the shaft 28 and this action is caused by the meshing of the worm 26 with the worm gear 33.

The controlling element 31 consists of a V-shaped trough 40 provided at its top with a pair of vertical extensions 41, 42, arranged in parallelism. The trough 40 is open at its outer end and is closed at its rear end by a rear wall 43, which has its top edge flush at the point of joinder of the extensions 41, 42 with the trough 40. Formed integral with the rear wall 43 is a rearwardly extending arm 44, which is positioned on the ledge 6 and abuts against the shoulder 7, and is detachably connected to the base member 1 by a hold-fast device 45 extended through the arm 44 and having threaded engagement with the wall of the opening 8. The cam 29 impacts against the inner faces of the extensions 41, 42 for imparting an oscillatory movement to the articulator member 9, and the pointed end 30 of the shaft 28 travels against the inclined faces of the trough 40 for imparting a vertical movement to the articulator 9 during the oscillatory movements thereof.

The detachable mounting of the controlling element 31 permits of different shapes of controlling elements being connected to the base member 1 to enable the grinding of the different slants on the cusps of the teeth and controlling elements of different shapes or contours are indicated at 46, 47 and 48 in Figures 7, 8 and 9 respectively. The element 46 has the sides 49 of its trough at an angle of forty-five degrees, the element 47 has the sides 50 of its trough at an angle of thirty degrees, and the trough 51 of the element 38 is of semi-oval shape. It is obvious that the troughs of the controlling elements can be of any shape desired for the purpose intended.

Arranged at the rear of the base member 1 and extending upwardly therefrom, is a supporting post 52, having a reduced peripherally threaded portion 53 for engagement with the walls of the opening 4. The reduced portion 53 provides a shoulder 54 which abuts against the upper face of the base member 1. The reduced portion 53 extends through the opening 4 and carries on its lower end a securing nut 55 which abuts against the lower face of the base member 1. The upper end of the post 52 is peripherally threaded, as at 56, and engaging therewith is an interiorly threaded cap 57 provided with a forwardly extending, angularly disposed arm 58 terminating in a spherical head 59, which is mounted in a spherical socket 60, formed in the head 61 of a bolt 62, which has threaded engagement with the wall of the socket 17. The head 61 and arm 58 are positioned in the cutout portion 13. The head 59, in connection with the socket 60, forms a universal

joint connection between the articulator member 9 and the post 52.

Formed integral with the rear of the articulator 9 is a pair of depending spaced curved arms 63, 64, which seat on a plate 65 slidably mounted on the post 52. Interposed between the plate 65 and the base member 1, and surrounding the post 52 is a coiled controlling spring 66 for the articulator 9, and said spring 66 normally tends to maintain the shaft 28 in the controlling element, and the vertical movement of the shaft 28 caused by the riding of the latter against the inner face of the trough of the controlling element is had against the action of the controlling spring 66.

The universal joint connection between the articulator member 9 and post 52 provides for the retruded and protruded positions of the articulator member during the operation thereof.

The ratio of the gear wheel 33 with respect to the worm 26 is preferably 30 to 1, but it is to be understood that the shaft 28 can be driven at any desired speed to provide for satisfactory grinding.

The universal or ball and socket joint connection enables free movement of the articulator member 9 and the latter is always under tension, due to the arrangement of the arms 63, 64 with respect to the spring controlled plate 65.

It is thought the many advantages of an articulator, more particularly to the imparting of an oscillatory and vertical movement to the upper articulator member, can be readily understood, and although the preferred embodiment of the invention is as illustrated and described, yet changes in the details of construction can be had which will fall within the scope of the invention as claimed.

What I claim is:—

1. A dental articulator comprising a base, a spring controlled upper articulator member arranged in superposed relation with respect to the base and having a universal joint connection at its inner end with the inner end of the base and revolute driven means carried by and depending from the outer end of said member and operatively engaging with the base at the outer end of the latter for imparting simultaneously an oscillatory and a vertical movement to said member, the controlling spring for said member resiliently maintaining the engagement of said driven means with the base.

2. A dental articulator comprising a base, a spring controlled upper articulator member arranged in superposed relation with respect to the base and having a universal joint connection therewith, driven means carried by said member and operatively engaging with the base for imparting simultaneously an oscillatory and a vertical move-

ment to said member, and means mounted in said member for operating said driven means.

3. A dental articulator comprising a base, a controlling element projected from the outer end thereof, a spring controlled upper articulator member positioned in superposed relation with respect to the base and having a universal joint connection at its inner end with the inner end of the base, and revolute driven means carried by and depending from the outer end of said member and extending in and engaging the upper face of said element for imparting simultaneously an oscillatory and a vertical movement to said member, the controlling spring for said member resiliently maintaining the engagement of said driven means with said element.

4. A dental articulator comprising a base, a controlling element projected from the forward end thereof, a spring controlled upper articulator member positioned in superposed relation with respect to the base and having a universal joint connection with the latter, driven means carried by said member and extending in and engaging the upper face of said element for imparting simultaneously an oscillatory and a vertical movement to said member, and means mounted in said member for operating said driven means.

5. A dental articulator comprising a base, a controlling element carried by the forward end thereof and provided with a trough portion, a spring controlled upper articulator member arranged over the base and having a universal joint connection therewith at its rear end with the base, and a driven means depending from the forward end of said member and having its lower end provided with means engaging the upper face of the trough portion of said element and further engaging with said element above the trough portion thereof for simultaneously imparting an oscillatory and a vertical movement to said member against the action of a controlling spring for the latter.

6. A dental articulator comprising a base, a controlling element carried by the forward end thereof and provided with a trough portion, a spring controlled upper articulator member arranged over the base and having a universal joint connection therewith at its rear end with the base, a driven means depending from the forward end of said member and having its lower end provided with means engaging the upper face of the trough portion of said element and further engaging with said element above the trough portion thereof for simultaneously imparting an oscillatory and a vertical movement to said member against the action of a controlling spring for the latter, and means mounted in said member for operating said driven means.

7. A dental articulator comprising a base, a spring controlled upper articulator member arranged in superposed relation with respect to the base and having a universal joint connection at its inner end with the inner end of the base and revoluble adjustable driven means carried by and depending from the outer end of said member and operatively engaging with the base at the outer end of the latter for imparting simultaneously an oscillatory and a vertical movement to said member, the controlling spring for said member resiliently maintaining the engagement of said driven means with the base.

8. A dental articulator comprising a base, a controlling element projected from the outer end thereof, a spring controlled upper articulator member positioned in superposed relation with respect to the base and having a universal joint connection at its inner end with the inner end of the base, and revoluble adjustable driven means carried by and depending from the outer end of said member and extending in and engaging the upper face of said element for imparting simultaneously an oscillatory and a vertical movement to said member, the controlling spring for said member resiliently maintaining the engagement of said driven means with said element.

9. A dental articulator comprising a base, a controlling element carried by the forward end thereof and provided with a trough portion, a spring controlled upper articulator member arranged over the base and having a universal joint connection therewith at its rear end with the base, and an adjustable driven means depending from the forward end of said member and having its lower end provided with means engaging the upper face of the trough portion of said element and further engaging with said element above the trough portion thereof for simultaneously imparting an oscillatory and a vertical movement to said member against the action of a controlling spring for the latter.

10. A dental articulator comprising a base, a post extended upwardly from the rear end thereof, an upper articulator member, a universal joint connection between the rear end of said member and said post, said member having a pair of depending arms

and the post provided with a spring coacting with the arms to form a spring controlling means for the member, a controlling element secured to the forward end of said base, and revoluble driven means depending from the forward end of said member and operatively engaging with the inner face of said controlling element for imparting simultaneously an oscillatory and a vertical movement to said member, said spring controlling means acting to permanently maintain said driven means in resilient engagement with the controlling element.

11. A dental articulator comprising a base, a post extended upwardly from the rear end thereof, an upper articulator member, a universal joint connection between the rear end of said member and said post, said member and said post having coacting elements to provide spring controlling means for the member, a controlling element secured to the forward end of said base, driven means depending from the forward end of said member and operatively engaging with the inner face of said controlling element for imparting simultaneously an oscillatory and a vertical movement to said member, and means mounted in said member for operating said driven means, said spring controlling means acting to permanently maintain said driven means in resilient engagement with the controlling element.

12. A dental articulator comprising a base, a post extended upwardly from the rear end thereof, an upper articulator member, a universal joint connection between the rear end of said member and said post, said member having a pair of depending arms and the post provided with a spring coacting with the arms to form a spring controlling means for the member, a controlling element secured to the forward end of said base, and revoluble adjustable driven means depending from the forward end of said member and operatively engaging with the inner face of said controlling element for imparting simultaneously an oscillatory and a vertical movement to said member.

In testimony whereof, I affix my signature hereto.

WILLIAM M. GAMBILL.
